UNITED STATES PATENT OFFICE.

WENDELIN WEIS, OF ST. PAUL, MINNESOTA.

BOX-FASTENER.

SPECIFICATION forming part of Letters Patent No. 227,082, dated April 27, 1880.

Application filed December 8, 1879.

To all whom it may concern:

Be it known that I, WENDELIN WEIS, of St. Paul, Ramsey county, Minnesota, have invented a new and useful Improvement in Devices for Egg-Case and other Box Fasteners, 5 of which the following is a specification.

The invention relates to fastenings for egg-cases and other boxes; and the object of it is to fasten the lids of egg-cases and other boxes 10 in such a way as to acquire greater convenience in opening and closing and more certainty in securing the same, as well as cheapening the cost of fastenings.

To accomplish this I construct a case or 15 box whose cover projects at each end to receive at right angles a wooden piece extending downward a short distance and fitting closely to the ends of the box or case. In the lower edge of each of such extensions is 20 cut the circular aperture, so as to leave a narrow opening thereto, just long enough to admit an oblong button when the length of the button is at right angles to the plane of the lid. This button is in length a little less 25 than the diameter of the aperture, and its ends are shaped to fit the sides thereof. This button is secured to one or both ends of the case or box by a tap-bolt, which passes into the case or box through an aperture in the 30 bottom of a deep cylindrical recess in the button. The recess receives a loose spiral spring of metal, fitting closely to its sides and extending from the inside of the head of the tap-bolt to the bottom of the recess in the 35 button.

In the drawings, Figure 1 is a view of the end of the case or box with the lid fastened on. Fig. 2 is a view of the recess, aperture, spiral spring, and tap-bolt in position, with 40 half the button cut away. Fig. 3 is a plan view of the button with the tap-bolt set.

In the drawings, A represents any ordinary box, and B its cover. The end pieces, b, of the cover, which come over the sides of the 45 box, have each a circular opening, C, with aperture or mouth D in the lower edge, and a bevel, d, all around its rim or circumference.

The button E is considerably longer than 50 wide, and has its ends rounded at e. It has a central cylindrical recess, J, open at the

bottom at G, and is fixed on the sides or ends of the box A by means of the screw-bolt H. This button is so fixed on the box that it may have a little motion in and out on the bolt H 55 by means of spiral spring K, resting at one end on the bolt-head I and at the other on the base of recess J.

To fasten the cover on the box the buttons are placed so that their length is at right 60 angles with the top, and thus each will readily pass into the mouths D of the openings C on the end pieces of the cover, and then, by turning the buttons around to or toward a horizontal position, their rounded edges being 65 especially adapted for this purpose, the cover is securely locked in place. The buttons will bind so firmly against the inside edges of C as to draw the cover tightly upon the box.

To remove the cover easy access can be 70 had to the button by means of the bevel on the edge of C, which will allow the thumb and forefinger to firmly grasp the sides of the button, and when the button is set vertically the cover will be released from the fastening 75 very readily.

It will be observed in the construction now shown that when the cover is thus fastened on the box its sides form shoulders or ledges, which will be of very considerable advantage 80 in affording hand-hold in lifting or moving the box.

Having thus described my invention, what I consider new, and desire to secure by Letters Patent, is—

1. The box A, having cover B, provided with 85 circular opening C, having mouth D on its lower edge and beveled rim d, in combination with the elongated button E, having rounded ends e, substantially as and for the 90 purposes set forth.

2. In combination with box A, having cover B, provided with circular opening C, having mouth D, all as described, the button E, rounded at e and recessed at J, and having 95 spring K, substantially as and for the purpose described.

WENDELIN WEIS.
